(57) **CLAIM**

The ornamental design for a cutting insert for machine tools for metalworking as shown and described.

DESCRIPTION

1. Cutting insert for machine tools for metalworking

1.1: Perspective

1.2: Front

1.3: Back

1.4: Top

1.5: Bottom

1.6: Left

1.7: Right

The broken lines shown in the drawings depict portions of the cutting insert for machine tools for metalworking which form no part of the claimed design.
